PUZZLE GAME

William H. Baynes, Los Angeles, Calif.
(4122 Greenbush Ave., Sherman Oaks, Calif. 91403)

Filed Mar. 23, 1973, Ser. No. 344,354

Term of patent 14 years

Int. Cl. D21—01

U.S. Cl. D34—15 M

FIG. 1 is a perspective view of a puzzle game showing my new design;

FIG. 2 is a top plan view thereof;

FIG. 3 is a side elevational view thereof; and

FIG. 4 is a bottom plan view thereof.

I claim:

The ornamental design for a puzzle game, substantially as shown.
